Term of patent 14 years

(Cl. D26—1)

FIG.1

FIG.3

FIG.4

FIG.2

FIG. 1 is a front perspective view of a photoelectric control unit, showing my new design;

FIG. 2 is a rear elevational view;

FIG. 3 is an end elevational view, partly broken away and cross-sectioned, the opposite end being substantially a mirror-image thereof.

FIG. 4 is a fragmentary perspective view on an enlarged scale showing the perforations in the front plate and back plate.

The perforations in the front plate in FIG. 1 are repeated as shown within the dotted line area.

We claim:

The ornamental design for a photoelectric control unit, as shown and described.
